UNITED STATES PATENT OFFICE.

LOUIS K. MARTIN, OF TORONTO, CANADA.

INFANT-EXERCISER.

No. 806,157.

Specification of Letters Patent.

Patented Dec. 5, 1905.

Application filed March 7, 1905. Serial No. 248,885.

To all whom it may concern:

Be it known that I, LOUIS K. MARTIN, of the city of Toronto, in the county of York, Province of Ontario, Canada, have invented 5 certain new and useful Improvements in Infant-Exercisers, of which the following is a specification.

The object of my invention is to devise a convenient, safe, and hygienic exerciser which 10 may be readily converted into a hammock; and it consists, essentially, of a jacket adapted to be connected with suitable supporting means, the jacket being of peculiar construction, and of a hammock extension adapted to 15 be connected to the jacket, the whole being constructed in detail substantially as herein-after more specifically described and then definitely claimed.

Figure 1 is a perspective front view of my 20 improved exerciser. Fig. 2 is a rear view of the same arranged as a swing. Fig. 3 is a perspective view of the device arranged as a hammock. Fig. 4 is a rear view showing the 25 method of connecting the hammock extension with the jacket. Fig. 5 is a sectional detail showing the method of adjusting the saddle.

In the drawings like letters of reference indicate corresponding parts in the different figures.

Referring particularly to Fig. 1, A is a coil-spring which may be attached in any suitable manner to a fixed point overhead. A cord B, provided with any suitable adjusting means, connects this spring with the cross-bar C, 35 provided with a hook D at each end. With these hooks are engaged the supporting-straps E of a jacket F, comprising a band and means for detachably connecting the ends of the band. In the drawings buttons e and suitable buttonholes are provided for this purpose. The jacket is provided with adjusting-laces G, which engage rows of eyelets at the 40 sides of the jacket. By means of these laces the circumference of the band may be adjusted to fit the child using the exerciser. A seat-flap H is secured to the jacket at the back and front by means of buttons f and buttonholes. As shown, the buttonholes are in the flap and a couple of sets of buttons are provided on the front of the jacket to permit of 45 the vertical adjustment of the seat-flap. The flap is rendered much more comfortable and hygienic for sitting by means of the saddle-pad I, which is provided with hooks a, which are adapted to engage the eyelets b in the flap. Sev-

eral sets of these eyelets are provided, so that the position of the saddle may be adjusted back and forth on the flap. (See Figs. 2 and 5.) To the supporting-straps E, I secure shoulder-straps M, preferably by means of buttons g and buttonholes. It will be seen that the child's arms will pass out between the supporting-straps E, over the sides of the jacket, and under the shoulder-straps M and his legs pass out under the sides of the jacket and over the seat-flap H. To the back of the jacket is secured a flap J, provided with buttons c, adapted to be engaged with buttonholes in the supporting-straps. When the device is being used as an exerciser, this flap is normally turned down somewhat 65 in the style of a sailor-collar; but when the device is to be used as a hammock the buttons are engaged with the buttonholes, and the flap J then forms a rest for the child's head. (See Fig. 3.) To complete the hammock, a hammock extension J' is buttoned to the back of the jacket, buttons h being provided at the back of the jacket for this purpose and suitable buttonholes in the hammock extension. The other end of the hammock extension is 70 provided with a cross-bar L, to which are connected the ropes intended to support the rear end of the hammock. For safety the sides of the hammock extension are provided with the side flaps N, which may be buttoned together 75 around the child, the buttons i, engaging suitable buttonholes, being provided for the purpose. Both flaps may also be buttoned to the front of the jacket. The button d is also provided at the bottom of the hammock extension, 80 adapted to engage suitable buttonholes in the side flaps of the hammock. All possibility of the child's slipping through the end of the hammock is thus obviated.

When the device is being used as a hammock 85 for any length of time, the flap H is preferably unbuttoned and extended flat. The saddle in this case would be removed. Of course the device may be used as a hammock with the flap H buttoned up, as shown. I prefer, however, 90 to extend the flap as suggested above, as this gives greater comfort to the child.

The supporting-straps E may be non-adjustable and permanently secured to the jacket; but I prefer to make them adjustable, as shown 105 in the drawings. For this purpose I connect a metal loop O to each side of the jacket at the front or back. Through this loop the supporting-strap is passed and its end buttoned to the main part by means of the but- 110

tons *j*, several buttonholes being preferably provided to give a range of adjustment.

So that the device may be employed as a swing, I provide the ends of the cross-bar *C* 5 with the eyes *P*. Suitable cords *Q* may be connected with these eyes and any suitable overhead support.

The exerciser described is found in practice to be convenient, safe, and hygienic, giving 10 the child both useful exercise and amusement. Owing to its ready adjustability, it may be adapted to children of different sizes and ages, and, owing to its ready conversion into a hammock, it may be found of great convenience 15 to mother and nurse when taking charge of a child.

What I claim as my invention is—

1. In an infant-exerciser the combination of a jacket; supporting-straps therefor; and a 20 hammock extension secured to the back of the jacket, substantially as described.

2. In an infant-exerciser the combination of a jacket; supporting-straps therefor; and a hammock extension detachably connected to 25 the back of the jacket, substantially as described.

3. In an infant-exerciser the combination of a jacket; supporting-straps therefor; a hammock extension secured to the back of the 30 jacket; a head-rest flap secured to the upper part of the back of the jacket; and means for detachably connecting the free edge of the flap to the supporting-straps, substantially as described.

35 4. In an infant-exerciser the combination of a jacket; supporting-straps therefor; a hammock extension secured to the back of the jacket; and a stiff bar secured to the free end of the hammock extension, substantially as 40 described.

45 5. In an infant-exerciser the combination of a jacket; supporting-straps therefor; a hammock extension detachably connected to the back of the jacket; and a stiff bar secured to

the free end of the hammock extension, substantially as described. 45

6. In an infant-exerciser the combination of a jacket; supporting-straps therefor; a seat-flap connected at each end to the jacket; a saddle; and means for adjusting the saddle back 50 and forth on the seat-flap, substantially as described.

7. In an infant-exerciser the combination of a jacket; supporting-straps therefor; a seat-flap connected to and vertically adjustable relative to the jacket; a saddle; and means for adjusting the saddle back and forth on the seat-flap, substantially as described. 55

8. In an infant-exerciser the combination of a jacket; supporting-straps therefor; a hammock extension secured to the back of the jacket; side flaps secured to the sides of the hammock extension; and means for detachably connecting the free sides of the flaps, substantially as described. 60

65 9. In an infant-exerciser the combination of a jacket; supporting-straps therefor; a hammock extension secured to the back of the jacket; side flaps secured to the sides of the hammock extension; means for detachably connecting the free sides of the flaps; and means for detachably securing the outer ends of the flaps to the end of the hammock extension, substantially as described. 70

10. In an infant-exerciser the combination of a jacket; supporting-straps therefor secured to the upper edge of the jacket back and front at each side of the median plane; shoulder-straps connecting the back and front of each supporting-strap; and a seat-flap connected at each end to the jacket, substantially as described. 75

Toronto, March 3, 1905.

LOUIS K. MARTIN.
